(57) **CLAIM**

The ornamental design for a low-profile folding rear sight, as shown and described.

DESCRIPTION

FIG. 1 is a first isometric view of the low-profile folding rear sight;

FIG. 2 is a second isometric view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is an isometric view showing the low-profile folding rear sight in a folded position.

The portions of the low-profile folding rear sight depicted in broken lines forms no part of the claimed design.
